UNITED STATES PATENT OFFICE

CHARLES AMÉDÉE CAMBAY, OF PARIS, FRANCE

AUTOMATIC COIN CONTROLLED TELEPHONE APPARATUS

Application filed January 3, 1929, Serial No. 330,001, and in France January 28, 1927.

My invention relates to an operating coin controlled apparatus for telephone calls of the kind in which the introduction of a coin or a counter in the apparatus frees a movable hook on which hangs the telephone receiver and consequently allows a call to be made.

The apparatus comprises a safety locking device which totally prevents calls being made when the time prescribed for the conversation is over; it will then be absolutely in order to get another connection to introduce another coin in the apparatus.

The balanced rocking device is moreover provided with a single operating pin which is moved either upwards by means of a heel integral with a connecting rod actuated by the liquid braking device in such a manner as to guide the coin in the till, or downwards by means of a spring abutment which causes the balanced rocking device to oscillate in the same direction in order to eject the coin.

Fig. 1 is a side view of the apparatus, the enclosing plates being removed, showing some of the parts, with the telephone hook in latched position.

Fig. 2 is a view similar to Fig. 1, showing the relation of the operating slide in front of the parts in Fig. 1.

The operating mechanism is contained in a narrow casing 1, Figs. 1 and 2, for attachment to a telephone and having apertures 3 through which passes the hook lever 4, on which the telephone receiver is hung.

The casing 1 contains a coin slot 6 for conducting a coin or token in such a manner as to act on a pivoted lever 7 whose one end projects into the path of the coin and whose other, hooked end, 8 engages a lug 9 on a latch 10 pivoted at 50.

The nose 10^a of the latch 10 normally lies over the telephone hook lever 4 and retains it in latched position until a coin falls on the lever 7 and releases the latch which is then retracted by a spring 11. A stop pin 10^c limits the movement of the latch 10 when releasing the lever 4.

The coin first strikes the end of lever 7 that projects into its path and liberates the latch 10, which in turn releases the telephone lever 4 and comes to rest on two pins 12 and 42

projecting into its path, as shown at 15 Fig. 3. These pins are supported by a member 13 pivoted at 14 so as to be swung either to the left for retention of the coin, or to the right to return the coin to the operator, as will be explained later.

In the upper part of the casing 1 is a plate 16 provided with vertical guide slots 17. Pins 51 pass through the slots for guiding the plate and are fastened on casing member 1. A spring 17^a is disposed on the plate 16 which engages a pin 10^b on the latch 10 to return it to latching position when the telephone receiver 5 is replaced on the telephone hook lever 4. The upper part of the plate 16 carries a lug at 16^a on which acts the end of a spring-retracted plunger 18 whose head 18^a is manually engaged to depress the plunger 18 and plate 16, which in turn may depress the hook lever 4.

At the lower end of the plate 16 is a projection 16^b carrying a pin 19 movable in a slot 20^a of a slide 20 that is operated by a liquid brake for timing the conversation.

This brake is situated at the bottom of the casing 1, and comprises a cylinder 21 containing oil or other liquid, and a piston connected by a link 22 to one end of a lever 23 pivoted at 24, and whose other end is pivoted to the lower end of the slide 20. The slide 20 is guided on the pin 19 by the slot 20^a.

A spring 25 serves to operate the brake after the deposit of the coin, times the conversation, and returns the slide 20 to its upper position.

The slide 20 carries an arm 20^b on which is fixed a bracket 43 having a lug 43^a positioned to act on the forward projecting end of the pin 42 at the end of the upward movement of the slide, to tilt the member 13 to retain the coin.

The bracket 43 is vertically adjustable by the screws and slots 53 with respect to the arm 20^b to vary the time at which the coin is ejected from the member 13 by a sooner or later contact of lug 43^a with pin 42.

The plate 16 carries at its lower end a yielding spring abutment 30 which can be moved to and fro in an inclined direction to act upon pin 42 to cause the member 13 to

move on its pivot to eject the coin for return to the operator when the receiver is hung up before the timing brake has finished its operating movement. This yielding arrangement of the spring abutment permits it to pass the pin after accomplishing the operation.

On the back of the plate 16 is mounted a latch 39, pivoted at 38 and whose one end is moved onto the hook lever 4 after a suitable time. On the latch is a lug 39^b having an elongated opening through which may slide a rod 40 on the upper end of slide 20 on which is a helical spring 41. This rod carries at its top, above the lug 39^b a regulating nut 40^a.

The free end of a spiral spring 44 engages the curved end 39^a of latch 39 and frictionally holds it in the position to which it has been moved.

20. The operation is as follows:

The telephone hook 4 being-latched a coin is inserted in slot 6 to release it. The coin falls onto the end of the lever 7 projecting into its path and operates the lever 7 to release the spring-retracted latch 10 which comes to rest against the stop 10^c. The coin continues its descent and is held by the two pins 12 and 42 on the pivoted member 13. The receiver 5 is then lifted from its hook 4 and the latter rises carrying with it plate 16, and the operator then asks for connection with the subscriber.

Upon the rising of plate 16 the pin 19 is lifted from the bottom of slot 20^a and the slide 20 is free to move upward under the action of the spring 25 on the lever 23 checked by the brake 21. The brake is timed for a definite interval, say sixty seconds. If communication is obtained before the sixty seconds have expired, the piston of the brake continues to descend to the bottom of the cylinder 21 until the time indicated has expired.

The lug 43^a on the plate 43 fixed on arm 43^b of slide 20 engages pin 42 of the pivoted member 13 and causes it to tilt and discharge the coin to the left for retention.

When the conversation has terminated the receiver 5 is hung up on its hook which is then lowered and plate 16 is moved down with it. Spring 17^a strikes pin 10^b to move the latch 10 into its latching position with the nose 10^a on top of the hook lever 4 and the hooked end of 7 engaging the lug 9.

55. Upon descent of the plate 16 the pin 19 strikes the bottom of its slot 20^a and causes the slide to descend with it and actuate lever 23 to stress its spring 25 preparatory to another call.

60. In case communication has not been established within the time allowed, the receiver is hung up and the brake has not yet completed its operation, so that lug 43^a has not engaged pin 42 of the tilting member 13, and the spring abutment 30 strikes the pin 42

and causes the member 13 to tilt to eject the coin to the right.

If a second, fraudulent, connection should be attempted, without replacing the receiver on its hook, by operating the plunger 18 or the hook lever 4, the plate 16 is depressed and lever 4 descends below the curved end 39^a of lever 39 and it moves over the telephone hook lever 4 under the pressure of spring 41. Under these conditions the slide 16 has been raised during the previous call; and the spring 41 is under compression against the lug 39^b of the latch 39 just at the moment when the compression of spring 41 is about to swing the latch 39 on its pivot 80 against the hook lever 4, so that when the latter or the plate is moved down, the curved end 39^a immediately passes above the hook lever 4, and the lever 4 cannot rise sufficiently to make a connection until another coin is placed in the apparatus.

What I claim and desire to secure by Letters Patent of the United States is:

1. An automatic telephone apparatus controlled by a coin or counter, which comprises an opening for the introduction of the coin, a chute, a locking lever for the receiver suspension hook, a rocking detent for the locking lever, said rocking detent being released by an inserted coin, a balanced rocking device, two pins provided on same in order to receive the coin temporarily, a third pin to actuate the rocking device, a liquid braking device, a rod connected to the braking piston, a spring actuated pivoted lever connecting the piston connecting rod to a slide, a heel attached to said slide acting upon the driving pin of the rocking device to compel it to oscillate to one side a movable plate actuated by the movements of the telephone suspension hook, a spring abutment upon said plate to compel the rocking device to oscillate to the opposite side, and a safety device actuated by the slide which is connected to the braking device in order to engage the hook lever when an attempt is made to call prior to the insertion of a coin.

2. A pay attachment for telephones having a receiver supporting hook, coin released latching means for the hook, a plate controlled vertically by said hook, and a spring-operated slide released by said plate; in combination with a pivoted means operated from the slide, positioned to engage the hook, to prevent a second call if the plate or hook are again depressed without insertion of a coin.

In testimony that I claim the foregoing as my invention, I have signed my name.

CHARLES AMÉDÉE CAMBAY.
